STRIP CUTTER AND MARKER

Clarence E. Ward, Mishawaka, Ind., assignor to
 Mishawaka Rubber and Woolen Manufacturing Company, Mishawaka, Ind., a corporation of Indiana

Application October 19, 1946, Serial No. 704,334

4 Claims. (Cl. 101—1)

1

This invention relates to an apparatus for cutting a continuous length of strip material into sections and for individually marking these sections at a fixed distance from one end and at a distance from the other end determined by the weight.

The invention is particularly applicable to cutting and marking tubular knitted fabrics used in the manufacture of woolen footwear according to the process disclosed in copending application of Sherman and Hanson, Serial No. 655,144 filed March 18, 1946, now Patent No. 2,467,237, but is not necessarily limited thereto. The knitted stock from which the footwear, or gaiters as they are commonly called, are manufactured is usually of irregular weight per unit length. As a result, finished gaiters made from stock cut to equal lengths vary in weight. To insure a uniform quantity of material for each gaiter produced it is necessary therefore to measure the knitted stock according to weight rather than according to length.

In closing the end of the tubular stock to form the toe of the gaiter, it is customary to employ a machine that stitches the tube together and at the same time trims off the stock immediately outside the seam. To guide the operator in sewing and trimming to the proper contour, it is necessary to provide a suitable marking on the face of the strip stock which can be easily followed.

Thus, the principal objects of my invention are to provide a machine which will continuously and automatically cut strip stock into successive sections the length of each of which is determined individually and selectively according to the weight thereof; to insure a high degree of accuracy of the sections as to the weight thereof irrespective of the length; to permit convenient regulation of the weight of the sections; to provide a contour marking across the face of each section and accurately located relatively to one end of the section; to apply the marking while the stock is in the position for cutting and simultaneously therewith; and in general to permit fabric strips or the like to be rapidly and accurately cut into lengths individually determined according to the weight thereof, these and other objects being accomplished as pointed out more fully hereinafter and as shown in the accompanying drawings, in which

Fig. 1 is a side view of the entire apparatus with a portion cut away, showing the strip stock as it advances under the marker and cutter to the weighing platform;

Fig. 2 is a perspective view of the marking device and feed rolls;

Fig. 3 is a section of Fig. 2 along the line 3—3;

Fig. 4 is a fragmentary view of the apparatus looking from the left of Fig. 1 and showing the

2

control mechanism for the feed rolls and for the marking device;

Fig. 5 is a diagrammatic view of the control mechanism;

Fig. 6 is a side view of the weighing scale; and Fig. 7 is a front view of the cutter.

In the disclosed apparatus a roll of strip stock, suitably mounted on the frame of the machine, is advanced by means of feed rolls under a marking device, through a cutter, and onto the inclined weighing platform of a scale. When a predetermined weight of stock has been fed onto the weighing platform, the advance of the stock is arrested, the marking device applies the contour marking to the face of the stock and the cutter shears off the section of stock on the inclined platform. All of these operations take place in rapid succession practically simultaneously. As soon as the section on the inclined platform is cut off it is immediately discharged therefrom whereupon the cycle of operations of advancing, marking and cutting is repeated.

As shown on the drawings, the machine frame, which is indicated generally by the reference numeral 10, has a pair of parallel spaced uprights near the lower ends of which are mounted open top bearings 11 in which is rotatably and removably supported a spindle 12 which carries the supply roll 13 of the strip stock 14 to be cut and marked according to the practice of the invention. Strip stock 14 is advanced through the machine by means of feed roll 15 mounted at the top of the frame 10 on shaft 28 which is journaled in bearings 17. The roll revolves in the direction indicated by the arrow. A ratchet device 19 prevents the roll 15 from revolving backwards. Tension roll 16, in running contact with feed roll 15 is carried by a shaft 20 which is journaled in a frame 18 which in turn is supported in open top bearings 21 at the upper ends of the aforesaid spaced uprights of the frame 10. The roll 16 may be raised by exerting a downward force on lever 23, which pivots at point 24 on frame 10 and is connected through the link 22 with the frame 18 at 25. Feed roll 15 is driven by means of chain 27 meshing with sprocket 28, rigidly fixed to shaft 28. (See Fig. 2.) Chain 27 is operated from the power source (motor 30) through a speed regulator 29 and a countershaft composed of aligned shafts 33 and 34 which are operated connectable through a clutch 35 (Fig. 4).

Shaft 33 is supported in bearings 31 and 45, which are bolted to the frame member 79, and has a sprocket 32 on the outer end, connected by the chain 36 with the drive sprocket 84 of the speed regulator 29. The shaft 34 has one end thereof supported in the clutch 35 and near the outer end is journaled in the bearing 72 bolted to member 79 of frame 10. Shaft 34 has on its

outer end a sprocket 31 around which the chain 27 is trained.

When clutch 35 is disengaged, chain 36 continues to drive shaft 33 but the shaft 34 merely idles until the clutch is shifted to couple shaft 34 to shaft 33 into a unit.

The lever 38 pivots at its center on pin 39 which is fixed rigidly to frame 10, to operate clutch 35. The lever 38 is moved back and forth by means of the piston 42 in air cylinder 41 and is fastened to a connecting rod at 40. Air brought to one end of the cylinder 41 through conduit 44 swings the lever arm 38 to the position shown in Fig. 4 engaging clutch 35. When air is introduced into the other end of cylinder 41 through conduit 43 the arm 38 is swung to the vertical position (shown in broken lines in Fig. 4) to disengage the clutch 35. The control means for operating the clutch and consequently the feed roll will be described in more detail hereinafter.

Mounted on a part 51 of frame 10 at the delivery side of the feed roll 15 is an inclined slideway 55 leading to the inclined platform 76 of a weighing scale by which the section of stock 14 to be cut off is measured.

A bridging 54 is secured to and extends over the slideway 55 to guide the stock 14 from the feed roll 15 to the cutter (indicated generally at 60) and to the weighing platform 76, and this bridging 54, which is of sheet metal and shaped substantially as shown in Fig. 3, has a marker duct 56 secured thereon and of substantially the configuration of the marking to be applied to the stock 14.

This marking, in the present case is of a shape corresponding to the toe end of the foot and the duct 56 is accordingly substantially horse shoe shape and provided with a series of perforations 51 through the bottom thereof registering with corresponding perforations 52 through the top of the bridging 54, through which said perforations a powder is blown onto the underlying stock to mark the path of stitching to be subsequently applied to close the toe ends of the cut off sections of the tubular strip 14.

This horse shoe shaped marking extends from one lateral edge of the strip 14 to the opposite lateral edge and at the ends of the series of horse shoe marking perforations the horse shoe shaped duct 56 may be provided with a cross duct 50 with several marking perforations at the ends thereof, as indicated in Fig. 2, to define more conspicuously the places where the stitching is to start and terminated at the edges of the strip.

Beyond the cross duct 50 the ends of the duct 56 are turned upwardly for convenient application thereto of hose connections 53 through which powder is supplied to the marking ducts 50 and 56.

For supplying the powder to the ducts 50 and 56 compressed air is supplied from a suitable source (not shown) through a pipe 90, a valve 46 and a pipe 49 to a powder box 58 which has an outlet at the top leading through a pipe 59 with branched terminals from the respective ends of which the hose connections 53 lead to the elevated ends of the marker duct 56.

The powder box has a filling opening normally closed by a cap 92, and the air inlet pipe 49 terminates close to the bottom of the powder box 58 so that air injected therethrough into the box 58 agitates the powder contents sufficiently to impregnate the air with the powder which is thus carried by the exhausting air through the outlet pipe 59 and hose connections

53 to the marker ducts 56 and 50 from which it is discharged from the perforations 51 onto the strip 14, and into the interstices thereof, under the bridging 54. The top plate of the bridging 54 should closely overlie the strip material 14 to which the powder marking is to be applied, as the powder discharged through the perforations 51 and 52 will otherwise fan out and result in an indistinct marking.

For operating the powdered air blast of the marker in proper timed relation with the other operations, the lever 38, which controls the clutch through which the feed roll 15 is operated, has a lateral extension 48 with cam 48^a on the underside arranged to control and operate the valve opening lever 47 of the air valve 46 when said lever 38 is adjusted to the position shown in dotted lines in Fig. 4, the arrangement being such that the cam 48^a engages the lever 47 and opens the air valve 46 upon disengagement of the clutch 35 so that the feeding of the stock is discontinued and the stock 14 at the marking location is stationary when the valve 46 is opened to operate the marker. The valve 46 is spring 25 operated so that it closes by spring pressure when the cam 48^a is withdrawn from engagement with the valve arm 47 and thus the air valve 46 closes in this initial shifting of the clutch lever 38 and before the feeding of the stock by the feed rolls 30 15, 16 is resumed. Thus it is insured that there is no movement of the stock while the marking is being applied thereto.

Friction between the stock 14 and the machine surfaces in contact therewith is reduced to a minimum by providing smooth, polished sliding surfaces in these areas. Accordingly, the inside surfaces of guide 54, the top side of base plate 55 and the scale platform 76 are chromium plated.

40 The cutter 60, illustrated in Fig. 7 is bolted at its base 62 to member 57 of frame 10. The knife blade 65 is fastened to sliding bar 64 by means of set screws 68. The bar moves up and down on posts 63 to have shearing cooperation with stationary blade 66 to effect a shearing action. 45 Blade 65 is inclined throughout its length as shown in Fig. 7 so that its contact with cooperating stationary blade 66 is progressive. The stock 14 slides over stationary blade 66 between guide 50 blocks 67 which position the stock directly under the knife blade 65.

An air cylinder 61 is bolted to the head member 74 of the cutter. Piston 69 moves up and down in response to compressed air introduced through conduits 70 and 71. The motion of the piston in cylinder 61 is imparted to knife blade 65 through connecting rod 73 which is pivoted at its lower end to slide bar 64. The compressed air is directed to the appropriate end of the cylinder in suitable timed relationship with other operations of the machine in a manner to be described.

60 A scale 75 is mounted on member 74 of frame 10, and has an inclined platform 76 one end of 65 which extends up to cutter 60 but free of all contact therewith, the angle of incline of the scale platform bed corresponding to that of the base plate 55 of the marker from which the stock 14 is fed to the scale platform 76. The details of the scale are shown in Fig. 6. In balance with platform 76 is a second platform 77 on which is placed a weight equivalent to the section of stock 14 to be cut from supply roll 13. When the scale 70 is balanced, a beam of light from incandescent lamp 80 which is normally focused on photoelect-

tric cell 81, is interrupted by indicator hand 82 which completely blocks light passage through aperture 78. The photo-electric cell 81 is, in conjunction with a series of relays, part of a circuit which energizes a solenoid 83. When the light beam from source 80 is broken, the coil of the solenoid is energized to operate air control valve 86 so as to supply air to the rear side of the piston 42 of the clutch operating cylinder and operate the clutch lever 38 to disengage the clutch 35. Said operation of the valve 86 also supplies compressed air to the top side of the piston of cylinder 61 so as to operate the cutter 60. Thus upon the interruption of the light to the photo-electric cell 81, the feeding of the stock 14 is interrupted, the cutter 60 operated to cut off the length of stock in the weighing scale and at the same time the marking device is operated to supply the marking to the end of the stock from which the weighed section is cut off. The quantity of stock on platform 18 is exactly the amount required to counterbalance the weights 85 on platform 11. When the stock on the platform 16 has been severed from the continuous length it quickly slides off the highly polished platform throwing the scale out of balance. Indicator hand 82 swings back to open aperture 78 and allows the light beam to once again fall upon the photo-electric cell 81. The air control valve 86 through the solenoid arrangement then reverses the operations causing the marker to stop application of powder, the cutter to open and the feed roll to advance stock. Exact construction details of the photo-electric cell-solenoid-air valve combination are well known and are not set forth here.

The valve 86 has four conduits connected thereto. The air supply enters through conduit 83 and is directed to the heads of cylinders 61 and 41 via conduit 81. When the valve 87 is returned to the normal position compressed air is supplied therethrough from the supply conduit 83 to the opposite ends of the cylinders 41 and 61. Conduit 88 exhausts air to the atmosphere. When the ducts of element 87 are in the position shown, compressed air through main conduit 81 and branches 43 and 71 forces the pistons of air cylinders 41 and 61 downwardly. Thus cutter bar 64 is operated to shear off while arm 38 of the clutch 35 is thrown into vertical position to disengage the feed roll 15 from the power source to stop the advance of the strip stock. At the same time the movement of arm 38 into vertical position causes triangular block 48^a on cross arm 48 to open valve 46 and allow air to force powder from container 58 through marking device 59. Thus we have three operations taking place as air is directed through conduit 81:

- (a) The advancement of the stock is arrested;
- (b) The cutter shears off the section of stock on the platform of the scale, and
- (c) The marking is applied to the face of the stock directly beneath marker 58, 59.

The air from the opposite ends of the cylinders is exhausted through conduits 44 and 70, into the valve through conduit 89 and out into the atmosphere through conduit 88.

On the opposite cycle the element 87 of the valve 86 is turned $\frac{1}{4}$ turn counterclockwise so that one duct now connects the compressed air supply conduit 83, to conduit 88 and thus into the opposite ends of cylinders 41 and 61. The second duct of element 87 joins conduit 81 with conduit 88 to exhaust the air from the cylinder as it is forced out through conduits 43 and 71 when the pistons move up. Now the cutter bar

is disengaged, the air to the marker is shut off as lever 38 moves away allowing a spring to close valve 46, and the clutch is engaged coupling shafts 33 and 34 to start feed roll 15.

It is desirable to stop the advancement of the stock before the operation of the cutter and the marker. I have effected the proper time relation between the cutter operation and feed by employing a cylinder for the cutter with a longer stroke and diameter than the cylinder for the clutch and by retracting the cutter blade 65 sufficiently above the stock 14 so that the clutch 35 is fully disengaged before the cutter blade 65 reaches the stock to be cut. By properly adjusting the position of triangular block 48^a on arm 48 the marking operation occurs while the stock 14 is stationary.

While I have shown and described my invention in a preferred form, I am aware that modifications can be made therein without departing from the spirit of the invention, the scope of which is to be determined by the appended claims.

What is claimed is:

1. In an apparatus of the class described for cutting strip material into individually measured and marked lengths, the combination of a strip weigher, a strip marker, a strip feeder which feeds the strip to the marker and from the marker to the weigher and a strip cutter between the weigher and strip feeder at a predetermined distance from the marker and operatively controlled by the weigher, and means for operating the marker in predetermined timed relation to the operation of the cutter.
2. In an apparatus of the class described for cutting strip material into individually measured and marked lengths, the combination of a strip marker, a strip feeder which feeds the strip to the marker, a weigher onto which the strip is deposited from the marker, and a strip cutter between the weigher and marker at a predetermined distance from the latter and operatively controlled by the weigher.
3. A method of making elongated individually marked blanks from a strip of blank stock, which said method comprises individually weighing and cutting from said strip successive portions thereof to form the blanks, and applying near one end of each portion a marking at a distance from the other end determined by said individual weighing of that portion.
4. A method of making elongated individually marked blanks from a strip of blank stock, which said method comprises individually weighing and cutting from said strip successive portions thereof to form the blanks, and, before cutting thereof from the strip, applying near one end of each portion a marking at a distance from the other end determined by said individual weighing of that portion.
